UNITED STATES PATENT OFFICE.

JESSE L. CARRIGAN, OF BIRMINGHAM, ALABAMA.

SCREEN DOOR OR WINDOW.

Application filed July 5, 1923. Serial No. 649,672.

To all whom it may concern:

Be it known that I, JESSE L. CARRIGAN, a citizen of the United States of America, residing at Birmingham, in the county of 5 Jefferson and State of Alabama, have invented certain new and useful Improvements in Screen Doors or Windows, of which the following is a specification:

My invention relates to an improvement in 10 screen doors or windows which are provided with means to permit the escape of flies and insects through suitable guarded top apertures, thus permitting the insects to pass out of a room or enclosure.

One object of my invention is to design 15 such a screen door or window with a view to reducing the added cost of manufacture to the lowest possible point while providing cross bars or plates adapted both to inter-

lock with and support the free edges of the 20 screen wire and also to reinforce the top corner joints of the door or window frame.

A further object is to so design the screen 25 door or window that an opaque spaced backing is provided in a novel and economical manner behind the outlet openings so as to afford a darkened background which will reduce to a minimum the probability of insects entering the room through the escape 30 openings. This arrangement is of particular importance at night where the light shining unobstructedly through the openings would tend to attract insects, mosquitoes and the like and cause them to enter the 35 room or enclosure.

My invention further comprises the novel 40 details of construction and arrangements of parts, which in their preferred embodiment only are illustrated in the accompanying drawings, in which:—

Fig. 1 is a front view of a screen door 45 equipped with my improved arrangement of screen wire, the molding being broken away to show how the top perforated plate reinforces the corner joint.

Fig. 2 is a rear elevation of Fig. 1.

Fig. 3 is a cross-sectional view taken on the line 3—3 of Fig. 1.

Similar reference numerals refer to similar parts throughout the drawings.

I have illustrated my invention as embodied in a screen door, but the door construction is typical of a screen window. As shown, the door comprises side bars or vertical members 1 and a top cross bar or mem-

ber 2, the latter bar being rabbeted to leave a shoulder 3 under hung along the inside bottom edge of the top member 2. The side members are similarly rabbeted to form shoulders 4 and thus a recessed seat is provided marginally about the frame which receives the screen elements which are applied as follows. A short transverse width of screen wire 5 is reinforced by having bent about its lower edge a metal strip 6 and its upper edge is folded into the joint 7 which connects it to the bottom edge of a relatively narrow metal plate 8, the upper edge of which is placed upon the shoulder 3 and the recessed upper ends of the shoulders 4. A 60 filler strip 9 is laid across the top edge of the plate 8 and side filler strips 10 are set in the recess formed at the top of the shoulder 4 of each side 1. The bottom reinforcing plate 6 lies against the inner wall of this recess on each side and the filler block is shaped to receive and hold the plate 8, joint 7 and plate 6 firmly in place and to lie flush with the shoulders 4. I superpose on the 65 filler bar 9 and the upper edges of the filler bars 10 a plate 11, similar to the plate 9, except that it is provided with a series of apertures 12 in its intermediate portion. The lower edge of the plate 11 is folded into a joint 13 which receives and interlocks it to the free upper edge of the main screen wire 14. A molding 15 is broken around the frame in the marginal seat and serves to hold the main screen 14 in place, nails being driven through this molding and through 70 the outer plate 11, the filler blocks 9 and 10 and the inner plate 8 into the shoulders 3 and 4; thus firmly and rigidly interlocking the wire supporting members in the frame and at the same time providing metallic corner braces for the upper corners of the frame. The plates 8 and 11 are preferably of substantially equal width and it thus follows that the inside plate serves as an opaque 75 background behind the openings 12 which will prevent an insect from without seeing light through these openings and having any inclination to enter therethrough. Moreover it causes the openings 12 to be much more visible to the insect which has passed up between the spaced screens 5 and 14 and come between the plates and will thus facilitate its escape through the openings 12.

My screen frame attachment is very 80 simply constructed, is economical, does not 85

105

110

materially affect the appearance of the door or window, materially increases the strength and salability of the same, and at the same time gives a very strong and firm mounting for the free edges of the screen sections 5 and 14. While I prefer to use the backing plate 8 as a separate metallic element, my invention contemplates the provision of this backing by any suitable means which will 10 leave sufficient clearance between it and the openings in the main outer screen with reference to which it serves as an opaque background.

Though I have described with great particularity the details of the embodiment of the invention herein shown, it is not to be construed that I am limited thereto, as changes in arrangement and substitution of equivalents may be made by those skilled in 20 the art without departing from the invention as defined in the appended claims.

Having thus described my invention, what I claim as new and desire to secure by Letters Patent, is:—

25 1. A screen frame having an outer sheet of foraminous material provided at its upper edge with exit openings for the escape of insects, an inner imperforate opaque wall spaced inwardly from and depending below that portion of the outer foraminous sheet in which the exit openings are provided, and a foraminous apron extending downwardly from said inner wall and adapted to form an open bottom trap between it 35 and the outer foraminous sheet.

2. A screen door or window frame in accordance with claim 1, in which said apron is formed by a narrow strip of foraminous material which is interlocked with and extends downwardly from the lower edge of said imperforate wall in spaced parallelism with said outer foraminous sheet.

3. A screen door or window comprising a frame having an outer sheet of screen wire, a top plate connected to the upper edge of said wire and extending across the frame, a second imperforate metallic plate spaced inwardly from said first mentioned plate,

and a section of wire screening connected to the lower edge of said inner plate and 50 mounted in the frame in spaced parallelism with the outer screen wire, there being openings provided in said outer plate only for the escape of insects.

4. In a screen door or window, a frame 55 having a marginal recess opening outwardly which is countersunk across its top and for a short distance down on each side, a short screen section mounted in said countersunk portion of the recess, filler blocks to fill out 60 the countersunk portion of the recess, and a main outer screen mounted on the inner walls of the recess and filler block, there being openings provided in the outer screen opposite said inner screen and spaced therefrom.

5. A screen door or window comprising a frame having a marginal rabbet on one side only, a main outer screen and its retaining molding mounted in said rabbet, a 70 top plate interlocked with the top edge of said screening and seated in the upper portion of said rabbet, a recess in the inner wall of said rabbet extending from near the top of each side across the top thereof and part way down the sides, a short transverse screen section having a narrow bottom plate and a wide top plate connected with its bottom and top edges respectively, said plates and inner screen being seated in said recess, filler 75 blocks to fill out said recess and fastenings extending through the molding, filler blocks and both plates to secure the same to the frame, there being insect escape openings provided in the top plate only of the outer 80 screen.

6. A screen door or window frame in accordance with claim 5, in which said plates at their edges form reinforcements for the upper corners, being attached to the side 90 and top members at each corner joint.

In testimony whereof I affix my signature.

JESSE L. CARRIGAN.
